Assignors to

North. Chase, & North. of same place.

Letters Patent No. 636. Dated March 21st, 1854.

The schedule referred to in these Letters Patent, and making part of the same.

To all whom it may concern:

Be it known that we, John F. Allan and Joseph Stewart, of the city of Philadelphia, and State of Pennsylvania, have invented a new and improved design for stoves, and we do hereby declare that the following is a full and exact description thereof, reference being had to the accompanying drawings, making part of this specification, in which

Fig. 1 represents a front plate,

Fig. 2, a side plate,

Fig. 3, a portion of the back plate.

Fig. 4, a portion of the top plate,

Fig. 5, an open work screen for the top.

Fig. 6, the hearth.

a, a, is a beaded border, surrounded by a projecting moulding d, d.

b, b, b, are mouldings. c, c, c, are foliated ornaments for the corners. e, e, e, are vine-wreathed arches, springing from pilasters f, f, f. g is a shell-work ornament for the hearth.

What we claim as our invention, and desire to secure by Letters Patent, is

The design and configuration of the ornaments and mouldings herein described, forming an ornamental design for stoves.
